CLAIM

We claim the ornamental design for a truck, as shown and described.

DESCRIPTION

FIG. 1 is a front view of the truck;
 FIG. 2 is a left side view of the truck of FIG. 1;
 FIG. 3 is a right side view of the truck of FIG. 1;
 FIG. 4 is a top view of the truck of FIG. 1; and,
 FIG. 5 is a perspective view of the truck of FIG. 1.
 Features in broken lines show portions of the truck that form no part of the claimed design.

1 Claim, 5 Drawing Sheets(56)
